UNITED STATES PATENT OFFICE.

LEWIS D. WHIPPLE, OF GROTON, CONNECTICUT, ASSIGNOR OF ONE-HALF
TO FRANK L. MINER, OF PHILADELPHIA, PENNSYLVANIA.

MACHINE FOR SHARPENING RAZORS.

SPECIFICATION forming part of Letters Patent No. 659,501, dated October 9, 1900.

Application filed June 1, 1900. Serial No. 18,709. (No model.)

To all whom it may concern:

Be it known that I, LEWIS D. WHIPPLE, of Groton, in the county of New London and State of Connecticut, have invented a Cutlery-Sharpening Machine, of which the following is a specification.

This invention relates more particularly to mechanism for sharpening razors; and its primary object is to provide improved means for producing a smooth fine edge.

In the accompanying drawings, Figure 1 is an end elevation of mechanism embodying my invention. Fig. 2 is a sectional view thereof, taken on the line 2 2 of Fig. 1; and Fig. 3 is a sectional view taken on the line 3 3 of Fig. 2.

As illustrated by the drawings, the base 1 supports two pairs of struts 2 and 2', which support the respective shafts 3 and 3', journaled therein. The shafts 3 and 3' have the respective cylindrical sectors 4 and 4' fixed thereto and the respective intermeshing gear-wheels 5 and 5' fixed thereon. The gear-wheels 5 and 5' are arranged so that the disks 4 and 4' do not come together, but alternate in passing the place common to the path of each, and they are caused to travel in the directions of the arms by turning to the right the handle 6, which is screwed upon the shaft 5, and hence cannot turn the disks backward. The revolutions of the disks 4 and 4', as described, cause their leather-covered or other character of surfaces 7 and 7' to alternate in rubbing the corresponding edges of the blade 8, which is clamped and held in position by the arms 9 and 9', the arm 9 being provided with the jaws 10 and 10', connected by the pivot 11 and controlled by the screw-threaded key 12. The arms 9 and 9' are preferably rigidly connected, as by the member 9''. They are held in laterally-adjustable relation to the disks 4 and 4' by means of the horizontal bars 13 and 13', having slots 14 and 14' therein and the arbors 15 and 15' passing therethrough and screwed into the arms. These arbors are screwed up to a tension sufficient to hold the arms in fixed position normally, but permitting them to be rocked slightly by the alternating impact of the disks

4 and 4' with the blade 8. The arms are rendered adjustable vertically by means of the slots 16 and 16' in the struts 2 and 2', through which the clamp-screws 17 and 17' pass into the bars 13 and 13'.

It will now be seen that when a blade is held in place by the arms, as shown, and the handle is turned to the right the disks will alternately rub the opposite faces of the blade, which faces are held in movable relation to their corresponding rubbing-disks.

Having thus described my invention, I claim—

1. In a sharpening device, a pair of revolving cylindrical rubbing-sectors, in combination with means for holding a blade in the respective paths thereof, said sectors alternating in rubbing the faces of said blade, substantially as specified.

2. In a sharpening device, a pair of journaled shafts, a pair of cylindrical sectors and a pair of intermeshing gear-wheels, fixed on said shafts, said sectors alternating in passing a place common to the path of both, and rocking arms for holding a blade in the path of each of said sectors, substantially as specified.

3. In a sharpening device, a pair of revolving cylindrical sectors, rocking arms for holding a blade in the path of each of said sectors, and means for adjusting the position of said rocking arms relative to said sectors, substantially as specified.

4. In a sharpening device, a pair of revolving disk sectors, a pair of intermeshing gear-wheels fixed to said sectors, in combination with rocking arms for holding a blade in the path of each of said sectors, said rocking arms being provided with clamping-jaws for holding said blade, and means for regulating the rocking resistance thereof, substantially as specified.

In testimony whereof I have hereunto set my hand, in the presence of the subscribing witnesses, this 22d day of May, 1900.

LEWIS D. WHIPPLE.
